UNITED STATES PATENT OFFICE.

GIUSEPPE NATOLI, OF NEW YORK, N. Y.

SPARK PLUG.

Application filed March 1, 1924. Serial No. 696,287.

To all whom it may concern:

Be it known that I, GIUSEPPE NATOLI, a subject of the King of Italy, residing at New York, N. Y., have invented certain new and useful Improvements in Spark Plugs, of which the following is a specification.

This invention relates to an improvement in spark plugs and has for its object to provide a construction which can be easily constructed and taken apart and can be made of a minimum number of parts. A further object of this invention is to provide a long and comparatively large receptacle around the central electrode for the purpose of cooling it, this receptacle being adapted to be filled with oil which acts as a medium for transferring the heat from the electrode. A still further object is to provide a means for allowing the escape of the volatilized oil but preventing the liquid itself from running out of the receptacle and this means comprises a valve situated in the closure of the cylindrical receptacle. A small hole is provided in the grounded electrodes for preventing the accumulation of oil to thus prevent the carbonization of the sparking points and its immediate surroundings.

Further objects will be apparent from the following specification taken in connection with the accompanying drawing in which:

Figure 1 is a longitudinal sectional view of the spark plug,

Fig. 2 is a side elevation thereof, and

Fig. 3 is a plan view showing the electrodes of the spark plug.

Referring to the drawing the shell or base member 1 is provided at its lower end with a screw-threaded section 2 into the lower end of which the grounded electrodes 3 are provided. These electrodes may be integral with section 2 as shown or may be made separately and then inserted and secured in any suitable manner. A small hole 4 is drilled through the electrode 3 in order that oil which may collect on them may run through the hole to thus prevent carbonization which might ultimately result in a short circuit. The core member 5 comprising a receptacle is made of any suitable insulating material but preferably of porce-

lain and is provided with the central electrode 6 which is preferably cast into the lower end 7 of the receptacle. The core is also provided with a shoulder 8 which extends around the core and thus forms a means of securing it into the shell. Packing ring 10 placed between the shoulder 8 and the shell 1 prevents the gases from escaping from the cylinder of the engine and the core 5 is secured in place by means of a securing nut 11. This nut 11 is threaded in shell 1 and bears down on shoulder 8 between which a packing ring 12 is provided. It is very essential that the space 9 in the receptacle be of considerable length and of sufficient breadth so that the electrode 6 will have a large area vertically for radiating heat therefrom to the oil contained in space 9, and that the oil or other suitable liquid directly contacts with the electrode.

The shell is closed at the top by means of a closure 13 through which the central electrode projects and in which is provided a vent 14 having a valve 15 therein. This valve is retained on its seat by means of a small spring 16 one end of which is secured to the closure 13 and the free end of which presses on the valve. Thus the plug may be turned or secured in any position since the oil contained in space 9 cannot flow out, yet if this oil should volatilize due to excessive heating, the vapor can escape through the vent and cause no injury to the shell. A small nut 17 is preferably threaded on the electrode 6 to fasten the lead wire thereto in the usual manner.

This spark plug can be easily taken apart for cleaning purposes by merely unscrewing the retaining nut 11 and lifting the core out of the shell.

I claim as my invention:—

1. A spark plug comprising a shell; a core in said shell having a long receptacle therein; a retaining nut for securing said core in said shell; an electrode secured in said core and extending vertically through said receptacle; a closure for said core having a vent therein; a valve for said vent; and means in said receptacle for cooling said electrode, said valve allowing the escape of

100

the cooling medium under excessive heating.

2. A spark plug comprising a shell; a core in said shell having a long receptacle therein; a retaining nut for securing said core in said shell; an electrode secured in said core and extending vertically through said receptacle; a closure for said receptacle having a vent therein; a valve in said vent;

and a cooling medium comprising oil in said receptacle adapted to surround and intimately contact with said electrode to cool it, said valve allowing the escape of the volatile oil upon excessive heating.

In testimony whereof I affix my signature,

GIUSEPPE NATOLI.
